UNITED STATES PATENT OFFICE

170,147

BASE FOR TABLE LAMPS

Edwin I. Cole, Eagle, Wis., assignor to The Stiffel Company, Chicago, Ill., a corporation of Illinois

Application February 25, 1953, Serial No. 23,791

Term of patent 7 years

(Cl. D48—20)

To all whom it may concern:

Be it known that I, Edwin I. Cole, a citizen of the United States of America, residing at Eagle, Walworth County, Wisconsin, have invented a new, original, and ornamental Design for a Base for Table Lamps, of which the following is a specification, reference being had to the accompanying drawing, forming a part hereof.

a larger scale taken on line 2—2 of Figure 1, and being partly broken away and in section.

I claim:

The ornamental design for a base for table lamps, as shown.

EDWIN I. COLE.
